UNITED STATES PATENT OFFICE.

JACOB KAUTZ, OF CHICAGO, ILLINOIS.

SHORE CLAMP.

Application filed October 18, 1926. Serial No. 142,426.

This invention relates to certain novel improvements in shore clamps and has for its principal object the provision of an improved construction of this character which will be highly efficient in use and economical in manufacture.

Among the several objects of the invention is the provision of a device of this character which will be positive in its operation and perform its duty with an assurance of safety.

A further object of the invention is the provision of a device of this character which can be manually forced into clamping relation with shore supporting bars for holding the bars in the required adjusted position and one which can not be easily thrown from operative position by objects striking thereupon or against.

20 Other objects will appear hereinafter.

The invention consists in the novel combination and arrangement of parts to be hereinafter described and claimed.

The invention will be best understood by reference to the accompanying drawings and in which:

Figs. 1 to 3 inclusive are detail views of the invention illustrating the same in various applied positions,

30 Fig. 4 is a sectional detail view of the invention taken substantially on line 4—4 of Fig. 1,

Fig. 5 is a sectional detail view taken substantially on line 5—5 of Fig. 4,

35 Fig. 6 is a plan view of one of the clamping elements embodied in the invention, and

Fig. 7 is a perspective view of another of the clamping elements embodied in the invention.

40 In the drawing 10 and 11 indicate two shore supporting bars which are adapted to be clamped in an adjusted position by means of my improved shore clamp generally indicated at 12. My improved shore clamp 45 includes clamping elements 13 and 14. The clamping element 13 is substantially U-shaped in plan view and has a bight portion 15 provided with an inner edge 16 forming a plurality of equally spaced apart teeth 17.

50 These teeth 17 have their under surfaces 18 beveled in an inwardly and upwardly direction for reasons hereinafter set forth. The limb portions 19 and 20 of this clamping element have their end portions bent 55 upon themselves to provide hook-shaped elements 21.

The clamping element 14 has depending portions 22 which provide guiding elements when the clamping element 14 is disposed transversely of the clamping element 13, 60 these guiding elements are adapted to embrace the outer edge portions of the limb portions 13 contiguous the hook-shaped ends 21. As shown in Fig. 7 the clamping element 14 has an edge portion 23 which provides a plurality of equally spaced apart teeth 24. These teeth 24 have their top surfaces 25 beveled inwardly and downwardly for reasons hereinafter set forth. The clamping element 14 is adapted to be positioned transversely of the clamping element 13 beneath the hook-shaped end portions 21 and when the clamping element 14 is in clamping position it is detachably latched from detachment with the clamping element 13 by a suitable latch 26. This latch 26 is pivotally connected to the limb portion 19 and provides an end portion 27 which is substantially U-shaped in cross section to embrace adjacent portions of the limb portion 19 of the clamping element 14. 75

80

In applying the clamping device in clamping position the bars 10 and 11 are adjusted in the desired position and after this has been accomplished the clamping element 13 is disposed to embrace the bars 10 and 11 in substantially the position illustrated in Figs. 1 to 3 inclusive. When the clamping element 13 is in this position the clamping element 14 is arranged in its proper position 85 with respect to the limb portions 19 and 20. In these positions it will be noted, Fig. 3, that the teeth 17 and 24 are in position to bite into the adjacent surfaces of the shore supporting bars 10 and 11. The next step 90 in applying my shore clamp is to draw the clamping elements so as to dispose the clamping element 14 in applied position upon the limb portions 19 and 20, it being pointed out that the hook-shaped end portions 21 serve as a pivot for the clamping element 14 which is drawn into clamping relation in the following manner. 95

100 A suitable tool is provided which includes a handle portion 28 and this handle portion 105 28 has an end portion 29 which is bifurcated as at 30. This bifurcated end portion is adapted to receive the body portion 31 of the clamping element 14. When the tool is in the applied position shown in Fig. 2 it is 110 manually drawn upwardly so as to pivot the clamping element 14 within the confines of

the hook-shape end portions 21. This pivotal movement draws the clamping element 13 into position to dispose the clamping element 14 flatly upon adjacent portions of the 5 limb portions 19 and 20, it being pointed out that the hook-shape end portions 21 function further to prevent displacement of the clamping element 14. When the clamping element 14 has been drawn tightly into 10 clamping position it will be noted that the teeth 17 and 24 will bite into adjacent surfaces of the bars 10 and 11 thus preventing relative movement of the shore clamp with respect to the bars 10 and 11. As will be 15 noted in Fig. 1 the bevelled surfaces 18 of the teeth 17 extend in a plane opposite the plane in which the bevelled surfaces 25 of the teeth 24 extend and this results in that fact that if an object should strike upon the 20 clamping element 14 it will tend to dig the teeth further into the adjacent surfaces of the shore clamp rather than displace the clamping element from clamping position with respect to each other.

25 When the clamping elements are in clamping position the latch 26 is brought into operation and functions to detachably latch the clamping elements together.

30 While I have illustrated and described the preferred form of construction for carrying my invention into effect, this is capable of variation and modification, without departing from the spirit of the invention. I,

therefore, do not wish to be limited to the 35 precise details of construction set forth, but desire to avail myself of such variations and modifications as come within the scope of the appended claim.

The invention having been set forth, what 40 I claim as new and desire to secure by Letters Patent is:

A shore clamp including a clamping element having one edge portion provided with teeth and oppositely disposed outwardly extending portions at the ends of said element 45 terminating in downwardly protruding portions, and a cooperating clamping element formed substantially U-shaped and having an edge portion provided with teeth and having portions providing a pivot for the 50 first mentioned clamping element, said downwardly protruding portions on said first mentioned clamping element engaging said second mentioned clamping element adjacent said pivot to limit transverse movement of said first mentioned element, said outwardly extending portions being adapted to be disposed on opposite sides of said cooperating clamping element, and a locking member pivotally mounted on one leg of 55 said U-shaped member and having a bifurcated portion adapted to be disposed to lock said clamping elements in clamping position.

In testimony whereof I affix my signature
JACOB KAUTZ
